DESIGN FOR A VOICE RECORDING MACHINE CASING

Charles C. Walker, Winfield, Iowa

Application March 9, 1945, Serial No. 118,382

Term of patent 14 years

(Cl. D56—4)

To all whom it may concern:

Be it known that I, Charles C. Walker, a citizen of the United States, residing at Winfield, in the county of Henry and State of Iowa, have invented a new, original, and ornamental Design for a Voice Recording Machine Casing, of which the following is a specification, reference being had to the accompanying drawing, forming part thereof.

Figure 1 is a top plan view of the voice recording machine casing of my invention; Fig. 2 is a front view of the voice recording machine cas-

ing of my invention; Fig. 3 is an end view of the voice recording machine casing of my invention; and Fig. 4 is a transverse sectional view taken on line 4—4 of Fig. 2, showing my new design.

The dominant features of my design reside in the portions shown by means of full lines in the drawing.

I claim:

The ornamental design for a voice recording machine casing, as shown and described.

CHARLES C. WALKER.
